Patented Sept. 23, 1958

183,556

FURNITURE LEG

Charles F. Close, Arlington Heights, Ill., assignor to
Arlington Seating Company, Arlington Heights, Ill., a
corporation of Illinois

Application July 25, 1957, Serial No. 47,076

Term of patent 14 years

(Cl. D33—14)

Fig. 1 is a side elevational view of a furniture leg, embodying my new design;

Fig. 2 is a front elevational view thereof;

Fig. 3 is a rear elevational view thereof;

Fig. 4 is an enlarged sectional view thereof taken along the line 4—4 of Fig. 1;

Fig. 5 is an enlarged sectional view thereof taken along the line 5—5 of Fig. 1; and

Fig. 6 is an enlarged sectional view thereof taken along the line 6—6 of Fig. 1.

The characteristic feature of my design consists in the provision of a vertical leg portion (shown in full lines) which tapers from a generally elliptical cross section with a centrally disposed groove on opposite sides of the larger

axis of the ellipse, the larger axis of the ellipse becoming smaller as the taper progresses.

The broken line showings of the desk top are for illustrative purposes only.

I claim:

The ornamental design for a furniture leg, substantially as shown and described.
